J. Sawyer

House Ventilator,

N° 14,642.

Patented Apr. 8, 1856.

UNITED STATES PATENT OFFICE.

JNO. SAWYER, OF FITCHBURGH, MASSACHUSETTS, ASSIGNOR TO HIMSELF AND THOS. HALE.

APPARATUS FOR HEATING AND VENTILATING BUILDINGS.

Specification of Letters Patent No. 14,642, dated April 8, 1856.

To all whom it may concern:

Be it known that I, JOHN SAWYER, of Fitchburgh, in the county of Worcester and State of Massachusetts, have invented an 5 Improved Apparatus for Heating and Ventilating a Building; and I do hereby declare that the same is fully described and represented in the following specification and the accompanying drawings, on which—

10 Figure 1, exhibits a front elevation of the same; Fig. 2, a side view of it; Fig. 3, a vertical, central, and longitudinal sectional of it; Fig. 4, a top view.

In the drawings A, exhibits an air heating chamber, within which there is arranged a smoke funnel or discharge flue B, the same being carried vertically through said chamber and opening out of an auxiliary stove or fireplace C, arranged inside 20 of the chamber A, as seen in the drawings. Without the said chamber A, there may be arranged a stove D, (for cooking or heating) having a winding or spiral funnel or discharge pipe E, arranged so as to extend 25 around and open into the smoke funnel B, hereinbefore mentioned.

Directly over the air heating chamber A, the smoke funnel B, is surrounded concentrically by a hot-air flue F, which rises above 30 the same and passes through a ventilating chamber G, arranged above and on the top of the air heating chamber A, as seen in the drawings.

Passages a, a, b, b, are formed through 35 both the top and the bottom of the ventilating chamber, the said passages having applied to them slide valves c, c, d, d, by which they may be opened or closed either in whole or in part as occasion may require. The 40 hot air flue F, at each of its ends is also provided with slide valves arranged as seen at e, e, in Fig. 4, the rods of the two lower valves of the said hot air flue, being exhibited at f, f, in Fig. 2. Each of said valves 45 is formed with a semi-circular recess or so as to embrace 180°, of the smoke flue and cover that much of the horizontal section of the air flue extending around the smoke-flue, each set of valves being arranged and applied so that its two valves may be moved in opposite directions. From the hot air 50 chamber A, one or more pipes, H, may extend so as to carry or lead heated air to one or more apartments in a story (of the build-

ing) which may be supposed to be arranged 55 directly above the hot air chamber, it being understood that the height of the hot air chamber is to correspond with or be about equal to that of the lowermost story of the building in which the heating and ventilat- 60 ing apparatus may be arranged.

In the application of such heating apparatus to a building, it is intended that the air heating chamber A, shall be placed in the lowest story thereof and also that the 65 ventilating chamber shall extend into the second as well as into each of the other stories, that there may be in the same building; or such story may have its separate ventilating chamber in which case the several 70 ventilating chambers would be disposed one over the other and having connection passages and closing valves to the same. The upper part or end of the air heating chamber, or the upper one of the series should be 75 made to open into or to have pipes of communication with the atmosphere whereby the foul air which may be received into the ventilating chamber may be suffered to escape into the said external atmosphere. In 80 order to ventilate, one or more stories through which the ventilating chamber may pass openings or pipes, I, K, (see Figs. 1 and 2) may be made in or let into the ventilating chamber from any room or rooms 85 of said story or from the upper and lower portions of any one room thereof; and should it be desirable to heat any of the rooms by means of separate stoves or fireplaces, they may be made to communicate 90 with the main smoke flue or funnel, B, by lateral pipes as seen at L, M, in Fig. 3. One or more dampers N, O, may be arranged in the smoke discharge flue as seen in Fig. 3, the rods being shown at g, g, in Fig. 2. By 95 means of the hot air flue, F, extending through the ventilating chamber, G, and surrounding the main smoke flue, not only may hot air be conveyed from the hot air chamber, A, into the third story of the 100 building, but the air passing up such flue may not only be further heated by that part of the smoke flue which is surrounded by the air flue, but said air may be used to impart heat to the ventilating chamber so as 105 to improve its ventilating powers or properties.

The object of the lower set of valves of

the ventilating chamber is to allow of the escape of hot air from the hot air chamber, whenever there may be a surplus of the same, and particularly in summer or warm weather when it may not be desirable to use the apparatus for warming the apartments.

I am aware that a smoke pipe has been inclosed in a casing so as to leave a space around the said pipe for the reception and 10 heating of external air and carrying the same into one or more apartments of a building. Therefore I do not claim such, but having made a peculiar combination and arrangement of the smoke pipe, air heating 15 chamber, hot air flue, and ventilating chamber, my invention rests thereon, and consequently

What I claim is—

The above described arrangement of the ventilating chamber G, with the main hot air flue F, the smoke flue B, and air heating chamber A, the ventilating chamber, and hot air flue having valves applied to them as specified, the whole being capable of being used in heating and ventilating the 20 25 apartments or stories of a building.

In testimony whereof I have hereunto set my signature this twenty-fourth day of December, A. D. 1855.

JOHN SAWYER.

Witnesses:

THOMAS C. CALDWELL,
ASA PARTRIDGE.
